UNITED STATES PATENT OFFICE.

RICHARD HUDNUT, OF NEW YORK, N. Y.

DESIGN FOR A BOTTLE.

SPECIFICATION forming part of Design No. 35,894, dated May 6, 1902.

Application filed March 31, 1902. Serial No. 100,849. Term of patent 7 years.

To all whom it may concern:

Be it known that I, RICHARD HUDNUT, a citizen of the United States, residing at Manhattan borough, New York city, in the county and State of New York, have invented and produced a new and original Design for Bottles, of which the following is a specification.

My invention relates to a new and original design for bottles and is illustrated in the accompanying drawings, in which—

Figure 1 is a front view of the bottle. Fig. 2 is a view of a side of the bottle.

The leading feature of my new design resides in a bottle ornamented upon three sides with a tracing in relief. The front ornamentation or tracing is what may be called a somewhat heart-shaped configuration or scroll, and each lateral ornamentation is in form of an arabesque or twist figure.

In the said drawings the letter *a* indicates the body portion of the bottle, which is rectangular in contour and converges at its top

into a cylindrical neck portion, the latter at its lower end having an annular bead or shoulder. The body portion of the bottle has on ²⁵ its front or on one of its wide faces the relief *b* of open or bulging configuration or, as it might be called, approximately heart-shaped outline. Each of the sides has the relief or ornamentation *c* of arabesque or twist form. ³⁰

My design presents a bottle having a novel, pleasing, and distinguished appearance.

What I claim as new, and desire to secure by Letters Patent, is—

The design for a bottle substantially as ³⁵ herein shown and described.

In testimony whereof I have hereunto set my hand in the presence of two subscribing witnesses.

RICHARD HUDNUT.
